UNITED STATES PATENT OFFICE.

BENJAMIN F. WOOD, OF MAPLEWOOD, NEW JERSEY, ASSIGNOR TO THE BABCOCK & WILCOX COMPANY, OF BAYONNE, NEW JERSEY, A CORPORATION OF NEW JERSEY.

BOILER FURNACE.

Application filed May 28, 1917. Serial No. 171,403.

To all whom it may concern:

Be it known that I, BENJAMIN F. Wood, a citizen of the United States, residing at Maplewood, in the county of Essex and State of New Jersey, have invented certain new and useful Improvements in Boiler Furnaces, of which the following is a specification.

My invention relates to boiler furnaces and will be understood by reference to the accompanying drawing in which Fig. 1 is a vertical longitudinal section, more or less diagrammatic; Fig. 2 a vertical longitudinal section of a modification; Fig. 3 is a sectional view showing the arrangement of the ventilating pipes; Fig. 4 is a sectional view showing the outer end of one of the ventilating pipes on a larger scale; Figs. 5, 6 and 7 show in detail one form of means for holding the bridge wall in alinement, while allowing free movement thereof in a generally vertical plane, Fig. 7 being a front view with some of the parts broken away along the line 7-7 of Fig. 6, Fig. 6, a vertical section on Fig. 7 and Fig. 5, a plan view, partly in section and on a reduced scale, of Fig. 7.

For the purpose of illustrating one application of my invention, it is shown in connection with a Babcock and Wilcox type of water tube boiler having an inclined bank of generating tubes 1 expanded into front and rear headers 2 and 3, the headers being connected in the usual manner to a longitudinal steam and water drum 4. In the space between the bank of tubes and the steam and water drum is a superheater 5. The bank of tubes is divided by baffles 6 and 7 into three transverse passes, the general course of the gases being indicated by arrows, the gases finally leaving the boiler through the outlet 8.

The boiler is shown as fired by an underfeed stoker of standard type the fuel being fed through retorts 9 into the furnace below the front wall 10. At its lower end the stoker is provided with the usual dumping plates 11. The pipe 12 is embedded in the side walls and from it a number of smaller pipes 12' pass through the wall and preferably terminate a short distance from the inner face of the wall, and opposite each pipe an opening 12" is left through the brick-work for the passage of air, as best shown in

Fig. 4. The same air blast which supplies the stoker supplies air to the pipe 12 and the air escaping through the smaller pipes flows upward along the face of the wall. This construction has been found highly efficient in preventing clinker from becoming attached to the wall.

At the rear of the furnace is a bridge wall 13 extending from the furnace floor to the lowermost row of tubes of the bank 1. A longitudinal baffle 14 extends from the upper end of the bridge wall to the baffle 6. The baffle 14 is shown as extending forward from a cross baffle 14' and as resting upon the tubes of the second row from the bottom so that the two lowermost rows are exposed to the radiant heat of the furnace for the length of the tubes which come above the furnace. This trapping out of the radiant heat assists in maintaining the furnace brick work as it causes a reduction in the furnace temperature. With the headers and baffles arranged as shown, it will be apparent that the gases in their upward movement over the boiler tubes are caused to pass over progressively decreasing flow areas.

In the lower part of the bridge wall 13 is an opening 15 closed by a suitable door 15'. This opening affords access through the bridge wall to the fire above the stoker and also for handling any clinker which may accumulate upon or above the dumping plates 11, and also for removing any clinker which may accumulate in the vicinity of the outlets of the small pipes 12'. A lower floor 17' is provided on which the operator would stand in getting access to the inner side of the bridge wall through door 15'.

In Fig. 2 a modified arrangement is shown in which there is an additional opening 16 through which rods may be introduced to scrape off any slag which may collect on the lowermost boiler tubes of the first pass.

Back of the bridge wall and above the opening or openings therein, is a floor 17 extending from the bridge wall to the rear wall 18 of the setting. A part of this floor is below the third boiler pass and any dust which is deposited from the gases as they flow through the second and third passes will accumulate in the pocket 19 from which it may be removed through the chute and

dumping device 20. The mud drum 21 may be protected by fire brick 22 from the heat which may arise through the combustion of the dust which collects in the pocket 19. A 5 baffle 23 prevents undue leakage of the hot gases around the mud drum by minimizing the suction at the rear of the headers 3.

Both the front wall 10 and the bridge wall 13 include courses of special tile 24 to 10 assist in holding the walls plumb. These tiles engage cast iron bulb pieces 25 so arranged that expansion in any direction cannot cause binding.

I have here shown the bulb pieces 25 provided with T-heads 26 engaging recesses 27 in the tiles. Said bulb pieces may also be provided with extensions 28, the ends of which engage the vertical flanges of angle-irons 29, the horizontal flanges of which 20 may be secured to a channel-iron 30 embedded in a recess in the flooring, as indicated in dotted lines in Fig. 1, and more fully in detail in Figs. 5, 6 and 7.

The means shown for holding the bridge 25 wall in vertical position are illustrative of only one of numerous means that could be used for this purpose and are substantially the same as those shown in the Jacobus Patent No. 1,341,645.

30 The provision of a roof or floor located above the boiler floor level at the rear of the bridge wall and the cross member associated therewith, and the connecting means between the bridge wall and the cross member, constructed and arranged to hold the bridge wall in alignment while allowing free movement thereof in a generally vertical plane, serves a most useful purpose in the case of high settings, such as illustrated in the embodiment of my invention as shown.

The inclined baffle 14 extending along the boiler tubes above the furnace chamber prevents the cold air which is drawn in through the access doors in the rear furnace wall 45 from laning through the furnace. Should the cold air which enters through the access doors be permitted to lane through the furnace and enter the spaces between the boiler tubes, it would result in strains due to unequal heating of the tubes and also lead to a loss in efficiency. The horizontal baffle causes the cold air which enters through the access doors to mingle with the furnace 50 gases making it pass longitudinally through the furnace, and thereby effectually prevents any such laning action.

What I claim and desire to secure by Letters Patent of the United States is:—

1. A steam boiler furnace and setting having a bridge wall, upper and lower floors 60 at the rear of said bridge wall forming a shielded space for an operator, the setting being provided with a dust pocket located above the upper floor and at the rear of said bridge wall, said bridge wall being provided with an opening for affording access to the furnace from said shielded space, and means for removing dust from said dust pocket.

2. A steam boiler furnace and setting having a bridge wall, upper and lower floors 70 at the rear of said bridge wall forming a shielded space for an operator, the setting being provided with a dust pocket located above the upper floor and at the rear of said 75 bridge wall, said bridge wall being provided with an opening affording access to the furnace from said shielded space, and said upper floor being provided with an opening through which the dust from said 80 dust pocket may be removed.

3. In a steam boiler, a furnace, boiler tubes located above the furnace chamber and inclined upwardly toward the front of the boiler, uptake and downtake headers to 85 which the tubes are connected, an under-feed stoker located beneath the uptake header and inclined in the same general direction as said boiler tubes, a rear furnace wall extending upwardly to said boiler tubes 90 and provided with an opening affording access to the dumping plates of said stoker, a baffle located above the furnace chamber for directing the gases forwardly, some of the boiler tubes being exposed to the radiant 95 heat of the furnace substantially the entire distance between said rear furnace wall and the front furnace wall.

4. A steam boiler furnace comprising a stoker, an air supply duct for delivering air 100 in close proximity to the inner face of the furnace side walls, a bridge wall at the rear of the combustion chamber and openings in said wall for the purpose described.

In testimony whereof I have hereunto 105 signed my name in the presence of two subscribing witnesses.

BENJAMIN F. WOOD.
